United States Patent Office.

REUBEN LIGHTELL, OF BROOKLYN, NEW YORK.

Letters Patent No. 101,892, dated April 12, 1870.

IMPROVEMENT IN SURFACE-CONDENSERS.

The Schedule referred to in these Letters Patent and making part of the same.

To all whom it may concern:

Be it known that I, REUBEN LIGHTELL, of Brooklyn, in the county of Kings and State of New York, have invented a new and useful Improvement in Surface-Condensers, of which the following is a full, clear, and exact description, reference being had to the accompanying drawing forming part of this specification, and in which—

Figure 1 represents a vertical longitudinal section of a surface-condenser, constructed in accordance with my improvement;

Figure 2, a vertical transverse section thereof, taken as indicated by the line $z z$ in fig. 1;

Figure 3, a plan of the same, in part, with the top or cover removed; and

Figure 4, a view in perspective of one of the sectional tube-frames, detached.

Similar letters of reference indicate corresponding parts.

My invention consists in a sectional surface-condenser, made up of a series of separate tube-frames, which are slid or let into their places in the case or shell of the condenser, preferably at some little distance apart, to form intervening vacuum and steam spaces, but practically constituting an elongated tube-surface, composed of detached structures, which largely facilitate both the construction and fitting together or repair of the condenser, and by employing only short tubes, packing the latter in the tube-sheets, to provide for expansion and contraction, may be dispensed with.

Also, the invention embraces a novel arrangement of the inlet and outlet to a condenser for the water used in effecting condensation, whereby a more perfect action or circulation is secured.

Referring to the accompanying drawing—

A represents the case or shell of a condenser, to which B is the inlet for the exhaust steam, and C a space or chamber for its collection, before passing through the tubes, in which it is condensed by the action of cold water surrounding said tubes.

Arranged within this chamber, so as to lie in front of the advance tube-sheet, is a perforated plate or shield, D, which operates to break the shock of the exhaust steam, and thereby to protect said tube-sheet from being battered and the joints disturbed; also, which serves to divide up the steam into small jets and prepare it for distribution through the tubes.

The tubes and sheets or plates I prefer to make in part of iron and in part of zinc, in place of using copper, to avoid that well-known injury to the boiler, when made of iron, which takes place from the use of copper in the condenser.

The tubular portion of the condenser is represented as made up of a series, consisting of any suitable number, of independent sections E E E, arranged, the one in advance of the other, preferably, with steam and vacuum spaces F F F in between them, of sufficient capacity to allow of a man entering the same, as re-

pair or other circumstances may require, but said tubular sections may be arranged closer.

Each of these tubular sections E E E is a perfect structure of itself, and can be made separately from the rest of the condenser, and be put in and removed from its place in the latter in a short time, and, when requiring repair, can be lifted out and another made to replace it.

The sections may be slid to their places down suitably-constructed grooves $a a$ in the sides of the shell, and there be corked or packed; but all packing of the tubes, to provide for expansion and contraction, may be dispensed with, and the tubes $b b$ be made fast to the tube-sheets $c c$, inasmuch as said tubes only being short, variation of temperature will not materially affect their length, and in making them fast they are more reliable.

By thus constructing the tubular portion of the condenser in section, with the tubes in their places, before fitting them within the condenser or shell thereof, the putting together of the condenser, especially on shipboard, is greatly facilitated.

The water of condensation arising from the passage of the steam through the tubes $b b$ of the tubular structures E E E and the intervening spaces F F F, is or may be passed from the rear of the condenser by a lower outlet, d , along side-passages $e e$, to the branch f , which connects with the pump.

The water to effect condensation is introduced by an inlet, G, near the forward end of the condenser, from above or over the tubes, and, after circulating among or around the tubes on their outside, the same is drawn or passed off, also from above, by an outlet, H, near the back end of the condenser.

This arrangement of the inlet and outlet in the upper portion of the condenser, at opposite ends thereof, facilitates the descent of the cold incoming water and ascent of the heated outgoing water.

To apply such arrangement to the sectional construction of the condenser hereinbefore described, each tube-section E E E is made to communicate at its bottom by an opening, g , with a lower passage, h , which establishes connection between the several sections for the water by which the condensation is effected.

What is here claimed, and desired to be secured by Letters Patent, is—

1. A surface-condenser, made up of independent and detachable tubular frames or structures E E E, arranged to intersect the shell, the one in advance of the other, substantially as specified.

2. The arrangement of both the inlet and outlet G and H for the water which effects condensation, on the upper portion of the condenser, and at opposite ends thereof, substantially as specified.

REUBEN LIGHTELL.
